UNITED STATES PATENT OFFICE.

CHARLES S. HASKELL, OF PHILADELPHIA, PENNSYLVANIA.

STEAM-ENGINE GOVERNOR.

SPECIFICATION forming part of Letters Patent No. 285,892, dated October 2, 1883.

Application filed September 29, 1882. (No model.)

To all whom it may concern:

Be it known that I, CHARLES S. HASKELL, a citizen of the United States, residing in the city and county of Philadelphia, State of Pennsylvania, have invented a new and useful Improvement in Governors for Steam-Engines, which improvement is fully set forth in the following specification and accompanying drawings, in which—

10 Figure 1 is a vertical section of the governor embodying my invention, in line *x x*, Fig. 2. Fig. 2 is a horizontal section in line *y y*, Fig. 1. Fig. 3 is a vertical section in line *z z*, Fig. 2.

15 Similar letters of reference indicate corresponding parts in the several figures.

My invention consists of a governor wherein the pressure of water or other fluid in connection with the steam-pressure is caused to control the steam-throttle or cut-off valve, 20 substantially in the manner hereinafter fully set forth.

Referring to the drawings, A represents the frame of the governor, on one end of which is mounted a wheel, B, having a cam-groove, 25 *a*, which receives the stems C of two pump-pistons, D, whose barrels are formed by walls in the frame A, said pistons extending parallel with the axis of the cam-wheel B, said axis or shaft having connected with it a spur, 30 band, or other wheel, D, which receives motion from the engine.

At the foot of each barrel of the pump-piston D is mounted a valve, F, above which is another valve, G, the latter opening into a 35 chamber, H, the two chambers H communicating and forming a compression-chamber.

In a cylinder, J, which extends from the head or plug O to the wall L of the frame A, is a piston, K, which passes through and beyond the chamber H, and is pressed toward the wall L by the spring M, which bears against said piston and the plug O at the end of the cylinder J, said piston extending parallel with the pump-pistons D, and having a vertical bore, *b*, and a horizontal bore, *c*, the latter communicating with the former and with the end of the chamber J adjacent to the wall L, and with a chamber, W, at the neck *d* of the piston, said chamber W being the equalizing-chamber.

50 In the top wall of the chamber J is an opening or port, N, and on the sides of said cham-

ber are supply-chambers P P, the bottoms of which extend under the seats of the valves F, or are otherwise in communication with said valves. (See Fig. 1.)

Overhanging the port N is the head or plug Q, which is connected with a screw, R, the latter being properly fitted to the frame A, and serving to adjust the extent which the port N 60 may be covered and uncovered.

When the piston K is pressed forward by the spring M against the wall L, the space around the neck *d* of said piston inclosed with in the walls of the cylinder J forms the chamber W, which serves as a passage for the fluid from the chamber H to and through the port N.

S represents a passage from the pressure-chamber H, through which the fluid is allowed to pass to the end of the steam-valve 70 stem T, which can be placed directly under the governor, as shown in Fig. 3; or it can be set in any convenient place, with a connecting-pipe leading thereto.

When the engine begins to move, causing 75 the wheel E to rotate, the pistons D are operated, the effect of which is to pump the water or fluid from the chamber or tank P into the compression-chamber H, creating a pressure in said chamber, which communicates its pressure 80 down through the passage S to the top of the steam-valve stem, also causing the fluid to flow out through the port N. Now, if there is more fluid forced into the pressure-chamber H by the pump-pistons D than will flow out at the port 85 N in the same time, the pressure in the chamber H will be increased, which will act directly on the steam-valve stem, moving the valve, and thus shutting off part of the steam, causing the engine to move more slowly until the pistons 90 furnish just as much fluid in a given time as will pass out at the port N in the same time. In order that the flow of fluid through the port N shall be regular and uniform, the pressure must always be the same in the chamber W and 95 at the port N, to produce which the spring M, in connection with the piston K, inclosed in the cylinder J, is used, and acts in the following manner: When the governor is at rest, there being no pressure in any of the chambers, the spring M causes the end of the piston K to remain at rest against the wall L, which brings the neck *d* of the piston K opposite the throat *x*, (see Fig. 3,) making a free passage for the 100

fluid from the chamber H through said throat x and chamber W to and out at the port N to the tank P. As the engine commences to move, causing the pistons D to operate, the pressure in the chamber H is increased, which pressure is communicated by the liquid out through the throat x to the chamber W through b and c to the end of cylinder J. When the pressure on the piston K exceeds the resistance of the spring M, the piston K moves forward, cutting off part of the flow of fluid at the throat x, which causes the pressure in the chamber W to remain always the same, no matter what the pressure may be in the chamber H, which will always be regulated by the steam-pressure.

As the amount of liquid forced in by the pistons D is governed by the speed of the engine, and the amount of escape is regulated by a steady and uniform flow of the liquid through the port N, it will be seen that any increased speed of the engine will cause an increased pressure in the chamber H and on the steam-valve stem T, forcing it down and shutting off the steam required.

If, by additional work or any other cause, the speed of the engine is decreased, the pressure in the chamber H will be reduced, and the steam-pressure on the opposite end of the steam-valve stem will force the steam-valve open, and admitting steam enough to cause the engine to keep up its uniform speed.

When it is desired to change the speed of the engine, the head Q is lowered or raised, whereby more or less of the port N is uncovered, and a greater or less volume of fluid is permitted to pass through said port in a given time.

Having thus described my invention, what I claim as new, and desire to secure by Letters Patent, is—

A spring-pressed piston adapted to automatically equalize the outflow of liquid, in com-

bination with a piston which forces the liquid against and past the first-named piston, and a throttle-valve arranged to be closed by the pressure of any excess of said liquid beyond 45 what escapes at the outlet.

The chambers J and P, having communicating port N, in combination with the piston K, which makes the flow of liquid uniform through said opening, the head Q, adjustable to 50 regulate the outflow of liquid through said opening, the piston D, and the throttle-valve operated by excess of liquid, substantially as and for the purpose set forth.

A receptacle which supplies the liquid to 55 the forcing-chamber and also receives it therefrom, in combination with pump piston or pistons, and a throttle-valve opened by the pressure of steam when the pressure in the forcing-chamber is materially reduced, and closed by 60 the pressure of the excess of liquid over what escapes at the outlet of said chamber, substantially as set forth.

The compression-chamber H, in combination with the piston K, the wall L, spring 65 M, the port N, and the passage S, leading to the steam-valve stem, substantially as and for the purpose set forth.

The chamber J, having a port, N, the regulating-piston K, and the supply-chambers P, 70 in combination with the adjusting head or plug Q, substantially as and for the purpose set forth.

The chamber H, chamber J, and passage S, in combination with the piston K, having 75 necks d d, and a bore, b c, substantially as and for the purpose set forth.

CHARLES S. HASKELL.
